UNITED STATES PATENT OFFICE.

IRA E. McCABE, OF CHICAGO, AND RAYMOND W. ARMSTRONG, OF WILMETTE, ILLINOIS; SAID ARMSTRONG ASSIGNOR OF HIS RIGHT TO THE ARCLESS CONTACT COMPANY, A CORPORATION OF ILLINOIS.

HERMETICALLY-SEALED ELECTRIC SWITCH.

Application filed April 14, 1926. Serial No. 101,887.

The present invention relates particularly to so-called mercury switches in which there is a body of mercury in a sealed receptacle through a wall of which extend leading-in wires terminating in contacts or electrodes that are adapted, in one position of the receptacle, to be engaged with the mercury so as electrically to connect them together; while, in another position of the receptacle, the mercury is carried away from one or both of the electrodes or contacts, interrupting the connection between the same.

In the present, highly developed type of mercury switch the receptacle is made of glass that is hermetically sealed, the leading-in wires are hermetically sealed in a wall of the receptacle, and the electrodes and the gaseous content of the receptacle are so chosen that there is practically no deterioration through lapse of time or long and severe use. The leading-in wires must be made of a material that has the same coefficient of expansion as the glass, so that the joints between the wires and the glass will not be broken because of unequal expansion as temperature changes occur. The electrodes, on the other hand, must be made of a material that will not be acted upon chemically by the mercury, and such material may have an entirely different coefficient of expansion than that of glass. In the ordinary commercial switches the leading-in wires are special copper clad wires, while the electrodes are made of iron. In the manufacture of these switches, because the iron has a different coefficient of expansion than has glass, it has been necessary to take great pains so to place the joint between a leading-in wire and its electrode, that the difference between the coefficients of expansion of iron and glass would not bring about a break in the seal, under temperature changes while, at the same time, the leading-in wires would be fully shielded against contact with the mercury. Perfectly made switches of this kind have therefore been expensive.

The object of the present invention is to produce a simple and novel construction and arrangement that will permit mercury switches to be completed, to the extent of

placing in position the electrodes and leading-in wires and forming the seal around the leading-in wires by automatic machinery, and thus greatly reduce their cost 55 of manufacture, by reducing the need for the extreme accuracy that it has heretofore been necessary to practice in locating a joint between a leading-in wire and an electrode, with respect to the glass through 60 which the leading-in wire passes.

The various features of novelty whereby the invention is characterized will herein-after be pointed out with particularity in the claims; but, for a full understanding of 65 our invention and of its objects and advantages, reference may be had to the following detailed description taken in connection with the accompanying drawing, wherein:

Figure 1 is a side elevation of a switch 70 arranged in accordance with the present invention, having short terminal conductors connected thereto; Fig. 2 is a view looking at the top of the device as it appears in Fig. 1; Fig. 3 is a side view, similar to Fig. 75 1, on a larger scale, a section of the switch being broken away; Fig. 4 is a top plan view of the switch on the same scale as Fig. 3; and Figs. 5 and 6 are views similar to Figs. 3 and 4 showing another embodiment 80 of the present invention.

Referring to Figures 1-4 of the drawings, 1 represents a glass receptacle that may conveniently be made from a piece of glass tubing closed at the ends. Within the receptacle is a small body of mercury 2. 3 and 4 are electrodes of iron or other suitable material in the form of eyelets; these eyelets having stems that are joined to leading-in wires 5 and 6. In assembling the leading- 85 in wires and electrodes in the switch, one end of the glass tube is heated; the electrodes attached to the leading-in wires are inserted in the heated end of the tube with the eyelets arranged parallel with each other; and the heated end of the tube is then flattened by applying pressure on opposite sides in a direction at right angles to a plane containing the leading-in wires thus forming a flattened neck 7. The leading-in wires, during the flattening of the end 90 of the tube, are held in such a position that

the flattened area will be certain to extend inwardly for a short distance along the stems of the electrodes, so as to seal the joints between the electrodes and the leading-
5 in wires. The electrodes need not be positioned with extreme accuracy, as it is not important whether the length of the stems of an electrode that is sealed into the glass varies a few hundredths of an inch.

10 There are several reasons why in the construction just described there will be no injury to the seal on account of a difference between the coefficients of expansion of the glass and of the material of which the electrodes are made. The leading-in wires of
15 the electrodes are small in diameter and are spaced apart along the long dimension of the cross section of the flattened neck of the tube, so that any plane parallel to the short dimension of this neck goes through only a single wire; and therefore the glass is strong enough to resist any breaking stresses to which it might be subjected on account of the tendency of the leading-in wires to expand more rapidly than the glass. Furthermore, the glass of the neck of the receptacle presents a large radiating surface which will insure rapid cooling of the stems. The eyelets also, present comparatively large cooling surfaces within the switch. Therefore the comparatively short stems are provided at both ends with cooling means that will prevent them from becoming overheated, in use, to such an extent as to injure the seal.

18 The electrodes 3 and 4 are each made of a piece of wire bent at the middle to form an eye, the free ends being bent radially from the eye and lying side by side to produce a double stem 10. Each leading-in wire abuts at its inner end against the ends of both members of the corresponding stem. When the parts are assembled as heretofore explained, the joint 11 between each double stem and its leading-in wire, lies somewhat outwardly of the inner edge of the flattened neck. It will be seen that the current flowing through a leading-in wire divides at the stem of the electrode, one-half flowing through one leg of the stem, and the other half flowing through the other leg. Therefore the tendency of the stems to become heated is greatly reduced because the value of the current flowing through each leg of the stem is only one-half of the total current.

26 In the arrangement shown in Figs. 5 and 6, all of the parts are the same as in the arrangement just described excepting that instead of making the electrodes in the form of eyelets, they take the shape of small discs 13. Each disc has a stem 12, joined to the corresponding leading-in wire, as indicated at 14, a short distance outwardly from the inner edge of the flattened neck. The discs

provide a larger radiating surface for the dissipation of heat that may be created in the stems, than do the eyelets, but otherwise the principles involved are the same in the construction shown in Figs. 5 and 6 as in 70 that illustrated in Figs. 1 and 2.

75 While we have illustrated and described with particularity only a few forms of our invention, we do not desire to be limited to the exact structural details thus illustrated and described; but intend to cover all forms and arrangements which come within the definitions of the invention constituting the appended claims.

80 We claim:

1. A device of the character described comprising a sealed glass shell having a comparatively wide thin solid neck extending outwardly from one end thereof, leading-in wires extending through said neck 85 and having electrodes extending into the chamber within said shell, said leading-in wires being spaced a considerable distance apart from each other in the direction of the long transverse dimension of said neck, said 90 electrodes being circular in shape, arranged adjacent said neck, and in parallel planes extending at right angles to the plane of the long dimension of said neck, thereby presenting comparative large cooling surfaces 95 within the shell whereby the temperature of the electrodes is reduced before they engage the glass seal.

100 2. A device of the character described comprising a sealed glass shell having a comparatively wide thin solid neck extending outwardly from one end thereof, leading-in wires extending through said neck and 105 having electrodes extending into the chamber within said shell, said leading-in wires being spaced a considerable distance apart from each other in the direction of the long transverse dimension of said neck, the electrodes being connected to the leading-in wires by joints encased within the neck, the 110 free ends of said electrodes being bent radially to form eyes adjacent said neck, said eyes arranged in parallel planes extending at right angles to the plane of the long dimension of said neck, thereby presenting 115 comparative large cooling surfaces within the shell whereby the temperature of the electrodes is reduced before they engage the glass seal.

120 3. A device of the character described comprising a sealed glass shell having a wide thin solid neck extending outwardly from one end thereof, electrodes within said shell having comparatively thin stems, and leading-in wires attached to said stems, the 125 stems of the electrodes being spaced apart from each other in the direction of the long transverse dimension of said neck, and the joints between the stems and the leading-in wires being embedded in said neck, said 130

electrodes being formed of wire bent at the middle to form eyes with the free ends extending radially from the eyes and lying side by side to produce double stems abut-
ting the respective leading-in wires, whereby current flowing through a lead-in wire di-
vides at the double stem and reduces the

tendency of the respective stems to become excessively heated at the said joint.
In testimony whereof, we sign this speci- 10
fication.

IRA E. McCABE.
